UNITED STATES PATENT OFFICE.

THEODORE R. TREIBER, OF KANSAS CITY, MISSOURI, ASSIGNOR TO THE KANSAS CITY BILLIARD TABLE MANUFACTURING COMPANY, OF KANSAS CITY, MISSOURI, A CORPORATION OF MISSOURI.

CONVERTIBLE BILLIARD-TABLE.

No. 834,693.

Specification of Letters Patent.

Patented Oct. 30, 1906.

Application filed August 1, 1905. Serial No. 272,218.

To all whom it may concern:

Be it known that I, THEODORE R. TREIBER, a citizen of the United States, residing at Kansas City, in the county of Jackson and State 5 of Missouri, have invented new and useful Improvements in Convertible Billiard-Tables, of which the following is a specification.

My invention relates to improvements in convertible billiard-tables.

10 The object of my invention is to provide a table that may be used as a dining or library table or converted into a billiard-table.

The invention employs a construction in which two sets of detachable marginal rails 15 are used interchangeably in connection with a table-bed for forming the two kinds of tables, releasable means being provided for firmly securing the rails to the bed, one set of rails having cushions disposed longitudinally 20 along their inner sides, the other set of rails, when properly positioned upon the bed, having their upper sides flush with the top of the bed.

My invention provides, further, resilient 25 means for securing each rail to the bed, thus compensating for wearing of the parts which hold the rails in contact with the bed. Other novel features are hereinafter fully described and claimed.

30 Figure 1 is a top view of the table, showing three cushion-rails mounted on the bed and one detached therefrom. Fig. 2 is a horizontal sectional view taken on the dotted line *i j* of Fig. 3 and showing a set of rails clamped 35 in position upon the bed. Fig. 3 is a vertical sectional view taken on a plane corresponding to the dotted line *k l* of Fig. 2 and showing the cushion-rails secured in position against the bed. Fig. 4 is an inner side elevation view of one of the end cushion-rails.

40 Fig. 5 is a vertical sectional view taken on the dotted line *c d* of Fig. 2. Fig. 6 is a side elevation view of my convertible billiard-table having a set of rails mounted thereon.

45 Fig. 7 is a vertical sectional view taken on the dotted line *e f* of Fig. 2. Fig. 8 is a vertical sectional view taken on a plane corresponding to the dotted line *g h* of Fig. 2 and showing a portion of the bed and one of the 50 rails employed for converting the table into a dining or library table. Fig. 9 is a perspective view of the table having mounted thereon the marginal rails employed to form

the dining or library table. Fig. 10 is a horizontal sectional view taken on the dotted line *a b* of Fig. 5 and showing one of the rail-clamps and parts connected therewith. Fig. 11 is a vertical longitudinal sectional view of one of the rails used for forming the dining or library table. Fig. 12 is a perspective view 60 of one of the brackets supporting one of the rail-clamps. Fig. 13 is a top view of portions of two rail-clamps and a part of one of the cam-bars having resilient cams, part of the bar being broken away and a part shown 65 in horizontal section. Fig. 14 is a cross-section taken on a plane corresponding to the dotted line *o p* of Fig. 2, showing one of the rails 14 mounted on the bed. Fig. 15 is a top view of the bed with slate removed 70 and rails 14 mounted on the bed. Fig. 16 is a cross-section taken on a plane corresponding to the dotted line *m n* of Fig. 15.

Similar characters of reference denote similar parts. 75

The bed may comprise any construction suitable for forming the bed of the billiard-table. The construction I prefer to employ consists of a rectangular horizontal frame comprising two parallel end and two parallel 80 side members 1, the frame having a central member 2 secured at its ends to the end members 1 and transverse horizontal members 3, connecting the member 2 and the side members 1. The frame is supported by two vertical legs 4, having secured upon their upper ends the members 2 and 3, respectively. Upon the frame 1 is secured another horizontal rectangular frame 5, having secured to its edges four horizontal marginal members 6, 90 which project above the surface of the body of the frame 5 and embrace the edges of a horizontal slab of slate or similar material 7, mounted upon the body 5 and having its upper surface covered by an ordinary cloth 95 cover 8. Upon the outer edge of each member 1 are secured a plurality of inverted-U-shaped brackets 9, the vertical arms of which are provided with transverse openings in which are respectively mounted, one in each 100 bracket, a series of inwardly and outwardly slidable clamping members 10, each provided with a vertical projection 11.

12 denotes each one of the four detachable marginal cushion-rails, adapted to be secured 105 to the edge of and projecting above the up-

per surface of the slab 7. Each cushion-rail 12 above the slab 7 is provided along its inner side with the ordinary resilient cushion 13, adapted to receive thereupon the impact of 5 the billiard-balls.

14 denotes each of the detachable marginal rails employed for converting the table into a dining or library table. The rails 14 when secured in position against the bed have their 10 upper surfaces flush with the top of the cover 8. The rails 12 and 14 below a horizontal plane corresponding to the upper side of the cover 8 are similar to each other in construction. Each of the rails 12 and 14 is provided 15 on its inner side with a horizontal longitudinal tongue 15, adapted to be fitted in a corresponding groove provided in the outer side of the adjacent member 6, which tongue serves to bring and retain the rail in position 20 upon the bed. Each rail 12 and 14 is provided on its under side with a series of vertical sockets 16, adapted to receive therein, respectively, the projections 11 and outer ends of the clamping members 10. When 25 the members 12 or 14, as the case may be, are mounted, as described, upon the clamping member 10, and said clamping members inwardly moved, the rails may be brought into the position shown in Figs. 1, 2, 5, and 7. 30 For inwardly and outwardly sliding the said clamping members 10 the following-described mechanism is employed: Upon the outer edge of each member 1 are secured in any desirable manner a plurality of horizontally disposed U-shaped brackets 17, the parallel arms of which are provided with transverse openings in which is slidably mounted a horizontal cam-bar 18, movable longitudinally relative to the adjacent member 1 and provided 35 on its inner side with a plurality of inclined faces or cams 19, adapted when the bar 18 is moved lengthwise in the proper direction to engage and force inwardly the clamping members or bars 10, mounted upon 40 that side of the bed. The outer edge of each bar 18 is provided opposite the cams 19, respectively, with a series of cams 20, adapted to engage the adjacent clamping bars or members 10 and having their faces so inclined as to force the said clamping-bars outwardly when the bar 18 is moved lengthwise in a direction opposite that which forces the bars 10 inwardly. For moving the bars 18 lengthwise in either direction any suitable 45 means may be employed. The mechanism which I prefer to employ for this purpose comprises the following-described mechanism: 50

A plurality of U-shaped brackets 21 are secured one to the outer edge of each member 1 adjacent one end thereof. The parallel arms of each bracket are disposed horizontally one above the other and are provided with vertical holes disposed one above the 55 other and in which are mounted, respectively,

the ends of a vertical rotatable shaft 22, having mounted thereon a horizontal pinion 23, the teeth of which mesh in a series of rack-teeth 24, provided in the outer edge of the adjacent bar 18. The lower end of each 70 shaft 22 is preferably squared, as shown in Fig. 7, so as to be gripped by a wrench (not shown) when it is desired to rotate the pinion, so as to move the bar 18, engaged thereby, lengthwise. The ends of the rails 12 and 75 14 are preferably beveled at an angle of forty-five degrees, so as to form, when fitted to the bed, miter-joints. When it is desired to use the table for a billiard-table, the pinions 23 are turned, as above described, so as to force 80 the bars 18 in a direction such that the cams 20 will engage the clamping members or bars 10 and force them away from the bed. The cushion-rails 12 are then mounted, as above described, upon the proper projections 11, 85 after which the pinions 23 are rotated so as to force the bars 18 in a direction such that the cams 19 will strike the adjacent clamping-bars 10 and force said clamping-bars inwardly until the rails 12 are brought tightly 90 against the adjacent members 6, as illustrated in Figs. 1, 5, and 7, at which time the ends of adjacent rails will be brought against each other.

If it is now desired to convert the table 95 into a dining or library table, the pinions 23 are turned so as to move the clamping-bars 10 outwardly, as hereinbefore described. The rails 12 are then detached by lifting them upwardly from the projections 11, after 100 which the rails 14 may be mounted upon said projections 11 and adjusted against the bed in the same manner as has been described with reference to the adjustment of the rails 12.

In order that compensation for wear of the 105 clamping-bars 10 and the cams which force them inwardly may be effected, so that the rails may always be held tightly against the bed when it is desired to so position them, I provide resilient means for forcing the clamping-members or bars 10 inwardly. For this purpose each bar 18 has mounted on its inner edge a plurality of cam-springs 26, each of which is secured at one end to the inner edge 110 of the adjacent bar 18 and is inclined horizontally inward relative to the said bar 18, the inclined face of each spring 26 being adapted to engage and force inwardly, when the bar 18 is moved in the proper direction, the adjacent clamping bar or member 10. To secure proper engagement of the clamping-bars 10 and the bars 18, connected therewith, the under side of each bar 10 is preferably transversely grooved to receive the cams of the bar on which it is mounted. 115 120 125

Having thus described my invention, what I claim, and desire to secure by Letters Patent, is—

1. In a convertible billiard-table, the combination with the bed of the table, of the 130

detachable marginal rails, rail - supporting means mounted upon the bed, and means by which the rails may be independently adjusted toward and from the bed.

5. 2. In a convertible billiard-table, the combination with the bed of the table, of the detachable marginal rails, supports mounted upon the bed and adapted to carry said marginal rails, and means for moving said supports so as to independently move said marginal rails toward and from the bed.

3. In a convertible billiard-table, the combination with the bed of the table, of the detachable marginal rails, means for supporting said marginal rails one adjacent each edge of the bed, a plurality of movable bars supported by the bed, and means by which, when said bars are moved, the marginal rails will be independently adjusted upon 20 their supporting means relative to the bed.

4. In a convertible billiard-table, the combination with the bed of the table, of the detachable marginal rails, independent means for supporting each rail upon the bed and adjacent to and parallel with one edge thereof, and means by which each rail may be independently moved upon its supporting means toward and from the bed.

5. In a convertible billiard-table, the combination with the bed of the table, of the marginal rails, means for supporting said marginal rails one adjacent each edge of the table, a plurality of members slidably mounted upon the bed, and means by which 35 when said members are moved the marginal rails will be independently adjusted relative to the bed.

6. In a convertible billiard-table, the combination with the bed of the table, of the detachable marginal rails, means for supporting said marginal rails adjacent the edges of the bed respectively, a plurality of slidable bars supported by the bed, and means by which when said bars are properly moved, 45 the marginal rails will be independently moved upon their supporting means relative to the bed.

7. In a convertible billiard-table, the combination with the bed of the table, of the detachable marginal rails, a plurality of supports for carrying said marginal rails respectively and movably mounted upon said bed, and means by which said supports may be moved so as to independently adjust the 55 said marginal rails toward and from the bed.

8. In a convertible billiard-table, the combination with the bed of the table, of the detachable marginal rails, a plurality of rail-supporting means each movably mounted 60 upon the bed, and a plurality of adjusting means each provided with means when properly operated for engaging and moving one of said rail-supporting means so as to move the rails carried thereby relative to the bed.

65. 9. In a convertible billiard-table, the com-

bination with the bed of the table, of an independently-detachable marginal rail, a rail-supporting means mounted upon the bed, and means for independently adjusting said marginal rail upon its supporting means toward and from the bed.

10. In a convertible billiard-table, the combination with the bed of the table, of an independently-detachable marginal rail, a rail-supporting means movable upon the bed, 75 and means for moving said rail-supporting means so as to independently adjust said marginal rail to different positions relative toward and from the bed.

11. In a convertible billiard-table, the combination with the bed of the table, of an independently-detachable marginal rail, a rail - supporting means slidably mounted upon the bed, and means for sliding said supporting means so as to independently 85 adjust the marginal rail carried by it toward and from the bed.

12. In a convertible billiard-table, the combination with the bed of the table, of a plurality of slidable rail-supporting devices 90 slidable upon the bed toward and from one edge thereof, an independently-detachable marginal rail supported by said devices and movable therewith to a position against the adjacent edge of the bed, and means for 95 moving said devices so as to independently adjust the rail toward and from the adjacent edge of the bed.

13. In a convertible billiard-table, the combination with the bed of the table, of an independently - detachable marginal rail, 100 slidable supporting means carried by the bed upon which the marginal rail is movable toward and from one edge of the bed, a movable member supported by the bed, and means by which when said member is 105 moved, the rail is independently moved upon its supporting means relative to the adjacent edge of the bed.

14. In a convertible billiard-table, the combination with the bed of the table, of an independently-detachable marginal rail, supporting means carried by the bed and upon which the marginal rail is movable toward and from one edge of the bed, a slidale bar 115 mounted on the bed and provided with means when moved in the proper direction for independently adjusting the rail upon its supporting means toward or from the adjacent edge of the bed, and means for sliding 120 said bar.

15. In a convertible billiard-table, the combination with the bed of the table, of a detachable marginal rail, supporting means carried by the bed upon which the marginal 125 rail is movable toward and from one edge of the bed, a slidale bar mounted on the bed and provided with means by which, when it is properly moved, the rail will be moved upon its supporting means against the adj- 130

cent edge of the bed, the bar being provided with a series of gear-teeth, and a gear-wheel rotatively mounted on the bed and engaging the teeth in said bar.

- 5 16. In a convertible billiard-table, the combination with the bed of the table, of an independently-detachable marginal rail, a plurality of rail-supporting devices movably mounted upon the bed, a bar slidably mounted upon the bed and provided with means for engaging and moving said devices and thereby independently adjusting said rail relative to one edge of the bed, and means for sliding said bar.
- 15 17. In a convertible billiard-table, the combination with the bed of the table, of a plurality of rail-supporting devices movably mounted upon the bed toward and from one edge thereof, a marginal rail detachably supported by said devices and movable therewith against the adjacent edge of the bed, a toothed bar slidably mounted upon the bed and provided with means for engaging and moving said devices, and a rotatable gear-wheel mounted on the bed and engaging the teeth of said bar.
- 25 18. In a convertible billiard-table, the combination with the bed of the table, of a plurality of inwardly and outwardly slidable rail-supporting devices mounted on the bed and having upward extensions, of a marginal rail adapted to rest upon said devices and having sockets to receive said extensions, and means for simultaneously moving said devices so as to force said marginal rail against the adjacent edge of the bed.
- 30 19. In a convertible billiard-table, the combination with the bed of the table, of a plurality of rail-supporting devices, inwardly and outwardly slidable upon the bed, a detachable marginal rail carried by said devices and movable thereby against the adjacent edge of the bed, a movable bar provided with a plurality of cams adapted when the bar is properly moved to engage and slide said devices, and means for moving said bar.
- 40 20. In a convertible billiard-table, the combination with the bed of the table, of a plurality of rail-supporting devices slidable inwardly and outwardly upon the bed, a detachable marginal rail carried by said devices and movable thereby against the adjacent edge of the bed, a slidable bar having a plurality of cams adapted when the bar is properly moved to engage and slide said devices, and means for sliding said bar.
- 45 21. In a convertible billiard-table, the combination with the bed of the table, of a plurality of rail-supporting devices movably mounted upon the bed, a detachable marginal rail carried by said devices and movable thereby against the adjacent edge of the bed, a movable bar provided with a plurality of cams for engaging and moving said devices, and means for moving said bar.

22. In a convertible billiard-table, the combination with the bed of the table, of a plurality of rail-supporting devices movably mounted upon said bed, a detachable marginal rail carried by said devices and movable thereby against the adjacent edge of the bed, a slidable toothed bar mounted on the bed and having a plurality of cams for engaging and moving said devices, and a rotatable toothed member mounted on said bed and engaging the teeth of said bar.

70 23. In a convertible billiard-table, the combination with the bed of the table, of a plurality of rail-supporting means each movably mounted on the bed and adapted each 80 to support and move a marginal rail against the adjacent edge of the bed, a plurality of marginal rails detachably mounted one on each of said supporting means, a plurality of movable bars mounted on the bed and provided with means for independently engaging and moving said several supporting means respectively, and means for moving said bars.

75 24. In a convertible billiard-table, the combination with the bed, of a detachable 90 marginal rail movable toward and from the bed, and resilient means for forcing the rail against the bed.

80 25. In a convertible billiard-table, the combination with the bed, of a detachable 95 marginal rail, a rail-supporting means mounted upon the bed, and resilient means for moving said rail-supporting means toward the bed.

85 26. In a convertible billiard-table, the 100 combination with the bed, of a rail-supporting means mounted upon the bed, a detachable marginal rail movable on said rail-supporting means toward and from the bed, a movable member provided with means, 105 when moved in one direction for moving the rail away from the bed, and resilient means for forcing the rail toward the bed when said movable member is properly moved.

90 27. In a convertible billiard-table, the 110 combination with a rail-supporting means mounted on the bed, of the bed, a detachable marginal rail mounted on said rail-supporting means, a slidable member movable backward and forward and provided with resilient means for forcing the rail-supporting means toward the bed when the slidable member is properly moved.

95 28. In a convertible billiard-table, the 115 combination with the bed, of a plurality of clamping members movable toward and from the bed, a detachable marginal rail carried by said clamping members, a slid- 120 able bar and resilient means by which, when the bar is properly moved, the clamping mem- 125 bers will be forced toward the bed.

100 29. In a convertible billiard-table, the combination with the bed, of a plurality of clamping members movable toward and from the bed, a detachable marginal rail car- 130

ried by said clamping members, a slideable bar, and resilient cams carried by said bar and adapted to engage and force said clamping members toward the bed when the bar is properly moved.

30. In a convertible billiard-table, the combination with the bed, of a plurality of detachable marginal rails movable toward and from the bed and against the respective edges thereof, and resilient means for forcing said rails against the bed.

31. In a convertible billiard-table, the combination with the bed, of two inter-

changeable sets of marginal rails, rail-supporting means mounted upon the body and provided with means for supporting one set of rails at a time, and resilient means by which the rails carried by said supporting means may be moved against the bed.

In testimony whereof I affix my signature in presence of two subscribing witnesses.

THEODORE R. TREIBER.
